UNITED STATES PATENT OFFICE.

ROBERT VIEGELMANN, OF NEW YORK, N. Y.

COLLAPSIBLE CONTAINER.

Application filed February 24, 1925, Serial No. 11,037, and in Canada June 13, 1924.

This invention relates to collapsible containers, such as are disclosed by Patent No. 1,504,920, which issued August 12th 1924, which containers are adapted for holding 5 tooth paste, shaving cream, face cream, and articles of a like nature.

The particular object of the present invention is to improve and simplify the construction of such containers which are adapted to 10 essentially a single use, which can be readily filled, easily closed and very conveniently discharged by the simple pressure of the fingers, without the use of closing caps, screw-threaded parts, or any other separate 15 parts.

In use, my invention is hygienic and anti-septic, since by reason of a single use, danger of contamination by germ-carrying is obviated.

With the foregoing and other objects in view, the invention consists of the novel construction hereinafter more specifically stated, illustrated in the accompanying drawings, wherein are shown improved embodiments, but it is to be understood that changes, variations and modifications may be resorted to without departing from the scope of the invention.

In describing the invention in detail, reference is had to the accompanying drawings which form a part of this specification and wherein like characters of reference indicate corresponding parts throughout the several views, in which,

Figure 1 is a side elevation of an oval shaped, open-ended shell for receiving a portion of material, which afterwards is to be sealed therein;

Fig. 2 is an edge elevation of the same;

Fig. 3 is a top plan view of the open end of the shell;

Fig. 4 is a side elevation of the shell with the end completely closed and sealed;

Fig. 5 is an end elevation thereof;

Fig. 6 is a side elevation of the shell, wherein the upper portion has additional sealing crimps;

Fig. 7 is a side elevation of a slightly modified embodiment of the container;

Fig. 8 is a side elevation of a still further modified embodiment of the invention;

Fig. 9 is an edge elevation of a portion of the container shown in Fig. 8 on an enlarged scale;

Figs. 10 to 16 are side elevations of further modified embodiments of the container, and

Fig. 17 is a perspective view illustrating the manner in which the contents of the container is squeezed out.

The body of the container embodying this invention may be of any suitable form, such as cylindrical or oval in cross section, but in the embodiment shown in the drawings the shell has been shaped to an oval cross section.

Referring to Figs. 1, 2 and 3, a shell 10, having a rounded, closed lower end is shown. This shell is in the nature of an open-ended capsule of an oval shape and is in condition to receive the contents to be placed therein and sealed.

In Figs. 4 and 5 is shown the oval shell having its upper part, through which the filling takes place, closed by permanently 75 folding over the corner parts 11, leaving an outlet 12, through which the contents may be discharged, which outlet 12 is then crimped and pressed together.

Fig. 6 shows also a body of oval form, 80 which upper both sides and tips are crimped along as is shown by 13, and the open edges 12 are pressed together. For closing these open side edges 13, they are double crimped tightly together. The opening 12 is only 85 crimped a single time so that a relatively small, but properly applied pressure releases it.

In Fig. 7 is shown a slightly modified construction, wherein the shell 14 is formed 90 of tubular material with the lower end 15 folded over and permanently pressed against the sides of the tube so as to permanently seal the lower end thereof. The upper portion of the tube is closed after the material 95 is inserted therein by folding over the corners 16 and pressing together and crimping the opening 17 in the manner above set forth. The tube may also be doubly crimped as indicated at 18, in addition to the folded 100 corner 16.

In Fig. 8 the container comprises a shell 19 constructed in a similar manner to the shell 14 shown in Fig. 7. In this form of container the opening 20 is positioned at one 105 side of the tube and the edges are pressed together with single crimp 21 therein, the major portion of the tube from the opening

20 to the other side is provided with double crimps 22 and the outer edges may be folded over on to the tube for further securing the tube closed. As shown, the folded portion 5 may be in two sections 23 and 24, one section folded under and the other section folded over.

In Fig. 9 I have indicated the preferred manner in which I form the interlocking walls for closing the end of the container. 10 As shown, the crimps are formed with a machine for depressing the portions of the tube material on each other in a slanting position as indicated at 22 in order to make 15 the crimped or stamped part more secure. The outer edges of the tube may be further interlocked in a permanent manner by folding as indicated at 23 and 24. The interlocking of the walls in the various embodiments herein described may be accomplished by crimping, folding, rolling, perforating, stamping, stenciling, soldering or other approved ways according to the degree of locking or fastening of the walls 20 desired for the different portions of the 25 containers.

In Fig. 10, a container comprising a shell 25 formed in the same manner as the shell 14 disclosed in Fig. 7 is employed. This 30 container is closed by folding the side portions 26 together leaving an opening 27 between them and pressing the portions of the opening together and providing a single crimp 28 for sealing the opening.

35 The container 29 disclosed in Fig. 11 is of similar construction and has its end 30 closed by folding the side portions of the tube together as indicated by 30 after the tube is filled. It will be seen in this form 40 of tube that by pressing the sides of the container the folded portion 30 thereof will release and allow the contents to be ejected.

A similar container shell 31 is shown in Fig. 12. In this embodiment the end of 45 the tube is rounded and portions of the sides of the tube are folded upon each other as indicated by 32. By pressing the sides of this container, one or more of the folded portions 32 will yield and permit the contents to be ejected.

50 The container 33 shown in Fig. 13 is constructed the same as that shown in Fig. 12 except that the end of the tube is provided with opening 34 between folded sections 35. 55 In this form of the container the walls of the opening are pressed together and provided with a crimp 36.

The container 37 shown in Fig. 14 is constructed similar to that shown in Fig. 8 60 and is provided with a cap member 38 which is adapted to slide over the folded closure portion 39 and opening 40.

In Fig. 15 the container 37 is provided 65 with a spring clip 41 which operates to seal the end of the container in a similar

manner as the cap 39. When it is desired to remove the contents from the container, the cap 39 or spring 41 is first removed from the container.

In Fig. 16, a container 42 of similar construction is disclosed having its end 43 sealed by folding the side portions of the tube upon themselves in locking engagement. This closure is provided with a wire reinforcing member 44 extending throughout the locked folded portion acting as a reinforcing member and has an exposed end 45 which may be grasped and drawn outwardly in a manner to tear the portion 46 or so much of the end 43 as is desired to 70 provide an opening through which the contents of the tube may be ejected. In addition to the folding of the end 43, this tube may also be provided with crimps 21 and 22 which maintain the container sealed 75 after the removal of the wire 44.

In Fig. 17 a tube constructed in the manner set forth is shown with the contents being ejected therefrom by pressing the sides between the thumb and finger. By means of 80 such construction a single application container is provided, which cannot in any manner become unsanitary and which avoids many of the objectionable features of 85 tubular containers now in use.

90 The material of the tube can be made of any suitable material, the form or shape can be round, square, oval or flat; the size depends upon quantity of contents, though 95 preferably only one application is intended.

100 Containers embodying my invention may be readily taken along on traveling trips and when used, are thrown away. Such containers are particularly applicable for medical and surgical uses, in that they provide 105 antiseptic means for each dose and when made of a suitable material, the discharge ends thereof can be readily sterilized before being used, and thereafter the contents discharged.

110 While several embodiments of the invention have been shown and described, it is clear that changes may be made therein without departing from the spirit of the invention as defined in the following claims.

115 What is claimed as the invention and is desired to be secured by Letters Patent is:

1. A collapsible container comprising a tubular shell of pliable material closed at one end and adapted to receive its contents 120 through its other end before the same is closed, closing means at said other end of the tube comprising side portions thereof permanently folded against the body portion thereof leaving a small outlet opening 125 between the ends of said folded side portions and the walls surrounding said outlet opening being releasably interlocked with each other for closing and sealing the container, but adapted to be separated by pressure of 130

the contents in the container when the container is collapsed for automatically opening the container under predetermined pressure for removal of the contents by continued pressure.

2. A collapsible container comprising a tubular shell of pliable material, one end of said tube being closed by a section of the lower end of the tube being folded upwardly and permanently bent upon the body portion of the tube, the other end of the tube being open for receiving the contents and thereafter having side portions at the open end thereof permanently folded against the body portion leaving a small outlet opening between the ends of said folded side portions, and the walls surrounding said outlet opening being releasably interlocked with each other for closing and sealing the container.

3. A collapsible container comprising a tubular shell of pliable material closed at one end and adapted to receive the contents through the other and before the same is closed, closing means for said other end of the tube comprising doubly crimped side portions, and portions between singly crimped whereby the contents in the container will be sealed, but the middle portion with the single crimp adapted to be separated to form an opening by pressure of the contents in the container when the container

is collapsed under a predetermined pressure for removing the contents.

4. A collapsible container comprising a tubular shell of pliable material having one of its ends closed and the other end of said tube having crimped and folded sections of its side walls for holding them together so as to seal the end of the tube and hermetically enclose the contents thereof, said crimped section of the tube adjacent the folded section being adapted to yield and allow the contents of the tube to be ejected through the opening formed in the crimped section, when pressure is applied to the sides of the tube.

5. A collapsible container comprising a tubular shell of pliable material having one of its ends sealed by being folded to closed position, and the other end of said tube having its walls across the end hermetically sealed to each other by folded and crimped sections for enclosing the contents of the tube, said end of the tube having the crimped section adapted to open to allow the contents of the tube to be ejected from the crimped section when pressure is applied to the side of the tube, while the folded section remains closed.

In testimony that I claim the foregoing as my invention, I have signed my name hereto.

ROBERT VIEGELMANN.
